UNITED STATES PATENT OFFICE.

FATE LYLE, OF BENTON, TENNESSEE.

AUTOMATIC TRAIN-STOPPING MEANS.

1,332,733.

Specification of Letters Patent.

Patented Mar. 2, 1920.

Application filed June 21, 1919. Serial No. 305,749.

To all whom it may concern:

Be it known that I, FATE LYLE, a citizen of the United States, residing at Benton, in the county of Polk and State of Tennessee, have invented new and useful Improvements in Automatic Train-Stopping Means, of which the following is a specification.

One of the objects of my present invention is the provision of a simple, reliable and durable installation for assuring the stopping of trains in the event of the same coming into close proximity to each other on the same track, thereby averting a collision.

Another object of the invention is the provision of an installation for the purpose set forth, of such character that trains may be stopped at different distances from each other according to the strengths of the outfitts for generating electric current, complementary to the trains; this provision obviating the necessity of dividing the track rails and the conductor rails into blocks separated by insulation, and depending for its action upon the resistance afforded by the track rails and the conductor rails to the passage of the electrical current.

Other objects and practical advantages of the invention will be fully understood from the following description and claims, when the same are read in connection with the drawings, accompanying and forming part of this specification, in which:

Figure 1 is a broken side elevation showing the locomotives of two trains, equipped with the best practical embodiment of my invention of which I am cognizant.

Fig. 2 is an enlarged transverse section taken through a portion of one of the locomotives, and illustrating a part of my novel equipment.

Fig. 3 is an enlarged detail view illustrative of another part of the equipment common to the locomotives, the elements in said figure being shown in the positions they occupy when the locomotive is running.

Fig. 4 is a similar view with the elements referred to in the positions they are caused to assume by an operation of my improvement.

Fig. 5 is a view diagrammatic in character and showing the installation as a whole.

Fig. 6 is a detail enlarged view showing one of the contact wheels and the mounting thereof.

Similar numerals of reference designate corresponding parts in all of the views of the drawings.

I have elected to illustrate my invention in a block system, but it is to be understood that I do not confine myself to the employment of the invention in a block system, for the reasons hereinbefore alluded to and hereinafter fully set forth in detail.

In furtherance of my invention, I provide conductor rails 1 and 2 alongside the track rails 3 and 4, and when the block system is adopted, the said conductor rails and track rails will be arranged in blocks, as clearly shown in Fig. 5.

I also equip each of the locomotives 5 and 6 with the apparatus shown best in Figs. 2 to 6. The equipment of each locomotive is identical, and therefore a detailed description of one locomotive equipment will suffice to impart a definite understanding of both. The equipment referred to comprises a throttle lever 7 having a detent 8 for coöperation with a segmental rack 9, and also having a handle 10, an engineer's valve 11, provided with a handle 12 in which is an aperture 13, a rod 14 passed loosely through the aperture 13 and headed at 15, and a block 16 connected to the rod 14 and also connected through a retractile spring 17 and a loop link 18 with the handle 10 of the throttle lever 7. Manifestly movement of the block 16 toward the left from the position shown in Fig. 3 to that shown in Fig. 4, will be attended by movements of the throttle lever 7 and the engineer's brake valve handle 12 in the same direction, with the result that steam will be cut off from the piston cylinders of the locomotive, and during the completion of such cutting off operation, the engineer's valve 11 will have been opened to effect such communication between the train pipe of a fluid pressure brake apparatus and the atmosphere as to bring the train to a gradual or service stop. In this latter connection, it will be noticed that there is considerable lost motion of the rod 14 through the aperture 13 of the handle 12 before the head 15 engages the said handle 12 to bring about movement thereof. It will also be manifest that when movement of the block 16 toward the right in Fig. 4 is permitted, there is nothing to prevent manual manipulation of the handle 12 and the lever 7 for the starting of the locomotive. It will also be no-

ticed here that the loop link connection of the spring 17 with the detent handle 10 does not interfere with the usual manual movement of the said handle 10. Each locomotive is also equipped with an electric motor 20, the armature shaft 21 of which is connected through a train of gearing 22 with the shaft 23 of a drum 24. Connected to and designed to be wound upon drum 24 is 10 a cable 25 that is looped about a sheave 26 on the block 16 and is connected at its opposite end with the frame of the motor 20. From this it follows that energization of the motor 20 will cause the before described movement of the block 16 toward the left in Figs. 3 and 4; also, that when the motor is de-energized, there is nothing to prevent the before-mentioned movement of the handle 12 and throttle lever 7 toward the right. 15 20 As will be readily understood from Fig. 5, each motor 20 has its poles electrically connected with contact wheels 31 and 32 complementary to one track rail 4 and one conductor rail 2, respectively; also, that the 25 wheels 31 and 32 of one locomotive are arranged for coöperation with the rails 4 and 2 at one side of the railway, and wheels 31 and 32 of the other locomotive are arranged for coöperation with the track rail 3 and 30 the conductor rail 1 at the opposite side of the railway. As shown in Fig. 6, each contact wheel is preferably carried in a hanger 33 and backed by a spring 34, and a conductive brush 35 on the hanger is preferably 35 employed in contact with the perimeter of the wheel to assure adequate passage of current to and from the wheel. Each locomotive is also equipped with contact wheels 31^a and 32^a; these latter contact wheels being 40 arranged to engage the track rail 3 and the conductor rail 1 at the opposite side of the railway with reference to the rails engaged by the contact wheels 31 and 32 of said locomotive. Any approved generating outfit 45 may be employed for supplying current to the wheels 31^a and 32^a, said outfit being carried by the locomotive. I prefer, however, to employ a generator 40 actuatable by movement of the locomotive and a storage 50 battery 41 electrically connected with the poles of said generator, and also electrically connected with the wheels 31^a and 32^a. I also prefer to employ the electrical connection between the generator 40 and the storage battery 41 with a switch 42, in order 55 that the generator may be cut out when the storage battery is adequately charged.

In the practical operation of my novel installation, it will be readily understood 60 that when two locomotives equipped with my improvement come into dangerous proximity to each other on the same track, the course of the electric current will be from the plus pole of one storage battery 41 to the 65 contact wheel 32^a belonging to the same lo-

comotive, then through the conductor rail 1, then through the contact wheel 32 of the locomotive, and through the motor 20 of said locomotive to actuate the same, and from the motor to the contact wheel 31 of the second-named locomotive, and then back by way of the track rail 3, the contact wheel 31^a of the first locomotive, and the electrical connection shown, to the minus pole of said storage battery. At the same time current will pass 75 from the plus pole of the storage battery of the second-named locomotive to the contact wheel 32^a thereof, and then by way of the conductor rail 2, the contact wheel 32 of the first-named locomotive and the electrical 80 connection thereof through the motor 20 of said locomotive, and then by way of the electrical connection shown at the right of Fig. 5, the contact wheel 31, the track rail 4, the contact wheel 31^a of the second-named 85 locomotive, and the electrical connection shown, to the minus pole of the storage battery 41 belonging to said locomotive. In consequence, the throttle lever 7 and the engineer's brake valve handle 12 of each locomotive will be actuated in the manner before described, so as to bring each locomotive to a stop and thereby avert a collision. 90

As hereinbefore suggested, the generating outfit of each locomotive may be of such 95 character as to supply either a strong current or a weak current to the electric motor complementary to the locomotive. From this it follows that the electric motors 20 of the locomotives may be made to operate 100 when the locomotives approach within a certain predetermined distance of each other—i. e., when the locomotives are in such proximity that the current afforded by the generating means is sufficient to overcome the 105 resistance offered by the track rails, and the conductor rails. From this it follows that the application of my invention is not restricted to a block system, but on the other hand the apparatus may be used to advantage 110 in conjunction with continuous track rails 3 and 4 and continuous conductor rails 1 and 2.

Having described my invention, what I 115 claim and desire to secure by Letters-Pat-ent, is:

1. In means for the purpose described, the combination of a throttle lever, a segmental rack complementary thereto, a detent carried by the lever for coöperation with said rack, the handle of an engineer's brake valve; said handle being apertured, a movable element equipped with a sheave, a rod connected with said movable element and movable loosely through the aperture in said valve handle 120 and provided beyond the handle with an enlargement, a retractile spring connected with the movable element, a loop link connecting said spring and the detent handle, a cable 125 passed about said sheave and fastened at one 130

end, and electro-mechanical means for taking up said cable to move the detent handle and throttle lever and the valve handle.

2. In means for the purpose described, the combination of a throttle lever, a segmental rack complementary thereto, a detent carried by the lever for coöperation with said rack, the handle of an engineer's brake valve; said handle being apertured, a movable element equipped with a sheave, a rod connected with said movable element and movable loosely through the aper-

ture in said valve handle and provided beyond the handle with an enlargement, a retractile spring connected with the movable element, a loop link connecting said spring and the detent handle, a cable passed about said sheave and fastened at one end, and an electric motor having a drum to which the opposite portion of the cable is connected and upon which said portion is adapted to be taken up. 15 20

In testimony whereof I affix my signature.
FATE LYLE.
